UNITED STATES PATENT OFFICE.

GEORGE SANDS, OF BEAVER FALLS, PENNSYLVANIA.

CAR-BRAKE SHOE.

SPECIFICATION forming part of Letters Patent No. 472,955, dated April 12, 1892.

Application filed November 7, 1890. Serial No. 370,641. (No model.)

To all whom it may concern:

Be it known that I, GEORGE SANDS, residing at Beaver Falls, Beaver county, Pennsylvania, have invented a new and Improved 5 Railway-Car-Brake Shoe, of which the following is a specification.

My invention relates to a combined wheel and rail brake, and has for its object to provide a brake of the character described which 10 when applied to the wheel will be automatically forced down upon the rail, acting as a drag.

Rail-brakes as generally constructed have a tendency to lift the wheels from the track 15 when the brakes are applied to the rails; but my invention is designed to avoid this evil.

With such objects in view my invention consists of a brake-shoe movably held within a clog, said shoe being adapted to be moved 20 down by the action of the wheel and drag on the rail when the brake is applied, said shoe being automatically returned as soon as the brake is released.

My invention consists, further, in certain details of construction and combination of parts, 25 as will be more fully hereinafter described and claimed.

In the drawings forming a part of this specification, Figure 1 is a side view of a wheel 30 with my brake arranged in connection therewith. Fig. 2 is a side view of the clog, and Fig. 3 is a view showing the interior of the clog. Fig. 4 is a vertical longitudinal section.

In carrying out my invention I arrange my 35 improved brake upon the front side of the car-wheel K, the brake bar or beam and means for applying the same being of the usual or any approved pattern. The shoe D is of such length as to extend a considerable 40 distance both above and below the center of the wheel, and the face that bears upon the wheel is grooved to receive the flange. The lower end of shoe is enlarged, as shown at a, said enlarged end being adapted to bear 45 upon the rail when the wheel is braked, as will be more fully explained hereinafter. The outer face of the shoe D is recessed or grooved, and in said recess is placed the clog F, said clog and shoe being connected by means of a 50 set-screw C and washer, the screw passing through the same, the clog being slotted at i, in which the screw works, whereby the shoe

is permitted to have a vertical movement. The inner face of the clog is recessed, as shown in Fig. 3, and in said recess, near the upper and lower ends of the same, are journaled the friction-rollers H H, said rollers bearing upon the outer face of the shoe D. A spiral spring M is secured at its lower end to the lower side of the recess in the clog, the upper end of said spring being secured to the under side of cross-bar B, formed in the recessed portion of the shoe D. The brake bar or beam is secured to the outer face of the clog F in the usual manner. 65

In the construction as described, when the brake is applied the shoe will be pressed against the tread and flange of the wheel, and, being arranged in front of the wheel, the shoe will be carried down, as shown in dotted lines, 70 the enlarged end or foot dragging on the rail and operating as a rail-brake at the same time it brakes the wheel, and by reason of the position of the foot when down it can readily be seen it cannot derail the wheel, as is usually 75 done with brakes now in use. The brake-shoe, extending a considerable distance above the center of the wheel, presents a large frictional surface and the wheel is braked more easily and the mechanism is not subject to 80 the jerking so common with ordinary brakes. When the shoe is drawn down, the spring M is compressed, the screw c working in the slot i, and the moment the brake is released the spring will bring the shoe back to its normal 85 position.

The clog working in the recess of the shoe and the end of the clog and shoe being closed, dirt, &c., is prevented entering the same and impairing the apparatus. If desired, the shoe 90 D and clog F may be rigidly connected by removing washer and tightening-screw, in which case the shoe will operate as an ordinary one, but with an exceptionally-large friction-surface, as shown by the dotted lines 95 w w, the power being applied at p.

Having thus described my invention, what I claim is—

1. In a combined wheel and rail brake, the combination, with a sliding brake-shoe 100 adapted to bear upon the wheel, the rear face of said shoe being recessed, of a stationary clog arranged within the recess in the shoe, said clog being connected with the brake-

beam and upon which the shoe slides, substantially as shown and described.

2. In a combined wheel and rail brake, the combination, with a stationary clog having a longitudinal slot through the same and friction-rollers upon its inner face, of a shoe adapted to bear upon the wheel and having its outer face recessed to receive the clog, a spiral spring arranged between the clog and shoe, and a screw passing through the shoe and working in the slot in the clog, substantially as and for the purpose described.

3. In a railway-brake, the combination, with the clog F, of the shoe D, secured to said clog by the set-screw c in such a manner that by removing the washer from the set-screw c and tightening said set-screw the shoe D will be made rigid with the clog F, thereby making the shoe solid, substantially as shown and described. 15

GEORGE SANDS.
